CUFFED SLEEVE CONSTRUCTION AND METHOD OF MAKING THE SAME

Leo J. Rothbarth, Bellefontaine Neighbors, Mo.

Application July 14, 1955, Serial No. 522,089

1 Claim. (Cl. 2—123)

This invention relates generally to the apparel art and more particularly to an improved sleeve construction for shirts and the like and a method of making the same.

The principal object of the present invention is to provide a novel cuffed sleeve construction formed from a single piece of material.

It is an important object also to provide a method for constructing a sleeve without placket slits or vents, facings, placket dressings or separate cuffs, and thereby avoid the practice of gathering, pleating or puckering the sleeve at the cuff.

Another object is to provide a sleeve construction which is more economically manufactured because of less cutting, less waste, less sewing, and less cost in finishing and pressing.

Another object of the present invention is to provide a sleeve and cuff construction which freely accommodates the arm, especially at the elbow; prevents drafts and other exposure of the arm due to the elimination of the placket opening; is ironed more easily due to the elimination of peats or puckets; is easily adjustable for different wrist sizes; and is more economically manufactured.

Another object is to provide a sleeve and cuff construction which obviates the problem of cutting, sewing and matching the sleeve and cuff when printed fabrics are used.

Another object is to provide a sleeve and cuff construction which is neat in appearance, simple in construction, and economical to manufacture.

These and other objects and advantages will become apparent hereinafter.

Briefly, the invention comprises a simple one-piece sleeve and cuff construction wherein the cuff is formed as a stitched fold and is of multi-thickness to anchor co-acting fasteners secured thereto.

The invention also consists in the parts and the arrangements and combinations of parts hereinafter described and claimed.

In the accompanying drawing which forms a part of this specification and wherein like numerals refer to like parts wherever they occur:

Fig. 1 is a front view of a shirt showing sleeve and cuff assemblies constructed in accordance with the teachings of the present invention.

Fig. 2 is a pattern layout of the sleeve, showing in broken lines the amount of waste material resulting from cutting the sleeve from the pattern.

Fig. 3 is a view similar to Fig. 2, but showing the material folded into cuff stitching position.

Fig. 4 is a cross-sectional view taken along line 4—4 of Fig. 3.

Fig. 5 is a view similar to Fig. 3, but showing the stitched material turned into cuff forming position relative to the sleeve.

Fig. 6 is a cross-sectional view taken along line 6—6 of Fig. 5.

2

Fig. 7 is a view showing the finished sleeve and cuff construction.

Fig. 8 is a cross-sectional view taken along line 8—8 of Fig. 7, and

Fig. 9 is a cross-sectional view showing a modification of the sleeve and cuff assembly.

Referring now to Fig. 1 of the drawing, finished sleeve and cuff assemblies 10 constructed in accordance with the teachings of the present invention and by the method hereinafter disclosed are shown assembled on a finished shirt 11. Inasmuch as the sleeve and cuff assemblies 10 are identical, only one will now be described in detail.

Fig. 2 shows that the sleeve and cuff assembly 10 is formed from a single piece of material, the pattern layout for the assembly 10 results in the formation of a sleeve body 12 and a cuff body 13 integrally connected along a common margin defined by a stitch line 14. The sleeve 12 has a shoulder edge 15, the cuff has a cuff edge 16, and the sleeve in final construction is adapted to be sewn along connecting longitudinal seam edges 17.

The cuff is formed in the body 13 by folding the same in such a way as to provide an inner ply 20 and an outer ply 21 connected along a fold line 22, the outer ply 21 being attached to the sleeve body 12 at the stitch line 14 and the cuff edge 16 defining the unattached edge of the inner ply 20. The fold line 22 also defines the outer marginal edge of the cuff 13 when finished on the sleeve 12, and a fold line 23 adjacent to and parallel with the stitch line 14 defines the inner marginal edge of the cuff 13 when finished. A longitudinal fold line 24 is provided intermediate the seam edges 17 extending from the shoulder edge 15 to the cuff edge 16, the fold line 24 defining the folded longitudinal margin of the sleeve 12 and cuff 13 when the sleeve and cuff assembly 10 is finished, as shown in Fig. 7.

The cuff 13 is provided with fastening means, such as a buttonhole 27, adjacent to the folded longitudinal margin 24 and a co-acting fastening means, such as a button 28, intermediate the folded longitudinal margin 24 and the longitudinal seamed edges 17.

The method of manufacturing the sleeve and cuff assembly 10 will now be described in detail. The pattern layout of the sleeve and cuff assembly 10 is blanked out by cutting the arcuate shoulder edge 15 from the rectangular material being used, the waste material resulting from this step being extremely small compared with prior art constructions and methods of manufacture, see Fig. 2. Inasmuch as the longitudinal seam edges 17 are substantially parallel, the problem of laying out and cutting a conventional tapered sleeve pattern on printed fabrics or the like is obviated, as will become apparent hereinafter.

When the pattern layout of the sleeve and cuff 12 and 13 has been blanked out by cutting the shoulder edge 15, the cuff 13 is formed by folding the inner ply 20 and outer ply 21 along fold lines 22 and 23 into three-ply relationship with the sleeve 12 so that the fold line 23 occurs at the outer margin of the sleeve 12, Figs. 3 and 4. The widths of the inner ply 20 and outer ply 21 are predetermined so that the cuff edge 16 will abut the fold line 23 when the cuff 13 has been folded.

The cuff 13 is then sewed, as at 26, along stitch line 14 so that the inner ply 20 and the outer ply 21 are maintained in folded relationship. The two-ply cuff 13 is then turned outwardly along stitch line 14 in unfolded relationship with the sleeve 12 so that the fold line 23 defines the inner margin and the fold line 22 defines the outer margin of the cuff 13. As shown in Figs. 5 and 6, the fold line 23 is positioned above the stitch line 14 to form a three-ply "French" cuff on the sleeve 12.

The next step in the manufacture of the present sleeve

construction is to fold the sleeve 12 and cuff 13 along the longitudinal fold line 24 so that the longitudinal seam edges 17 are positioned adjacent to each other. The seam edges 17 are then boxed and stitched in any suitable manner to form the longitudinal seamed margin of the sleeve and cuff assembly 10, Fig. 7.

The buttonhole 27 or the like is then formed in the cuff 13 adjacent to the longitudinal folded margin 24, and the button 28 or the like is attached to the cuff 13 intermediate the buttonhole 27 and the longitudinal seam 17. As shown best in Fig. 8, the buttonhole 27 is preferably formed through both sides of the cuff 13 adjacent to the fold margin 24 so that it will be strengthened by the four-ply material at this point. The button 28 is attached to one side of the cuff 13 and is supported on a two-ply material. Furthermore, a conventional interliner (not shown) may be stitched into the cuff 13 between the inner ply 20 and the outer ply 21 whereby the buttonhole 27 will be supported by six-ply material and the button 28 by three-ply material.

It is now apparent that the sleeve and cuff assembly 10 has been provided with less cutting and sewing than is required by conventional prior art constructions. Furthermore, the need for strengthening pieces, or placket slits, facings and placket dressings has been obviated. Inasmuch as the cuff 13 is formed integral with the sleeve 12 and with substantially parallel longitudinal margins, the problem of gathering, pleating or puckering the sleeve at the cuff in conventional tapered sleeve constructions is eliminated whereby easier finishing and pressing is facilitated.

The present sleeve construction also freely accommodates the arm, especially at the elbow, because of the fullness of the material at that point; and because of the elimination of placket vents or slits, the exposure of the arm to drafts, dirt and the like is prevented. In addition, the button 28 or other fastener may be positioned at any point on the cuff 13 to vary the size of the wrist opening.

When the sleeve and cuff assemblies 10 are buttoned, as in Fig. 1, the fold margin 24 is turned inwardly toward the seam margin 17 so that the buttonhole portion of the cuff 13 laps over the button portion of the cuff, a graceful taper thus being provided from adjacent the elbow to the wrist of the wearer. It is to be understood that the elimination of the placket vent enhances the safety of the wearer around machinery and the like, and that the fold or pleat formed by the overlapping of the folded margin 24 on the sleeve 12 in no way reduces this advantage inasmuch as any projecting object catching the fold would simply cause it to open up or unfold.

An important feature of the present sleeve construction is the simplicity with which patterned goods may be laid out for cutting. Inasmuch as the sleeve 12 and cuff 13 are integral, no matching is required thereby saving time and the material formerly lost by cutting.

Fig. 9 illustrates a simplified form of the invention which may be practiced when the sleeve and cuff assembly 10' is being formed from reversible goods, such as white shirt material wherein both sides of the cloth are identical. In this embodiment the cuff 13' comprises an inner ply 20' formed integral with the sleeve 12' and an outer ply 21' attached to the inner ply 20' along a fold line 22', the outer ply 21' having the cuff edge 16' formed on its unattached edge. The cuff 13' is formed by folding the blank along a fold line 30 adjacent to the cuff edge 16' and along fold line 22' whereby the former defines the inner margin and the latter defines the outer margin of the cuff 13'. The sleeve 12' and the cuff 13' are then stitched at a point adjacent to the inner margin.

It is to be understood that the foregoing description and the accompanying drawings have been given only by way of illustration and example, and that changes and modifications in the present disclosure, which will be readily apparent to all skilled in the art, are contemplated as within the spirit and scope of the present invention, which is limited only by the claim which follows.

What I claim is:

A cuffed shirt sleeve formed throughout from an elongate single piece of material, the sleeve having at one end an edge for attachment to the shoulder of a shirt and having an under-arm seam extending through the entire length thereof, a cuff formed of the said material by an upturned upper fold, an outer downturned fold and an upturned lower fold, said lower fold and said outer fold forming respectively inner and outer plies of the cuff material, said lower fold having an edge portion located between the upper fold and the outer fold, the said upper fold, the said edge portion of the lower fold and the outer fold being joined together by a line of stitching whereby there is formed a tuck above the stitching defining the top of the cuff, a button secured to the outer face of the cuff by stitching passing through the said inner and outer plies and spaced a substantial distance widthwise of the sleeve from the under-arm seam, and a button hole formed through four plies of the cuff material and bordered by stitching passing through said four plies, the said button hole being spaced a substantial distance from the button on the side of the button remote from the under-arm seam, said button and button hole being adapted to secure the cuff in a folded condition.
